US0D1105070S

(12) **United States Design Patent** (10) **Patent No.:** **US D1,105,070 S**
(45) **Date of Patent:** **** Dec. 9, 2025**

(54) **SMARTWATCH**

(71) Applicant: **Shenzhen Yiqingteng Electronic Technology Co., Ltd.**, Guangdong (CN)

(72) Inventor: **Daoyuan Zheng**, Guangdong (CN)

(73) Assignee: **Shenzhen Yiqingteng Electronic Technology Co., Ltd.**, Shenzhen (CN)

(**) Term: **15 Years**

(21) Appl. No.: **29/970,454**

(22) Filed: **Oct. 29, 2024**

(30) **Foreign Application Priority Data**

Oct. 21, 2024 (CN) 202430661194.4

(57) **CLAIM**

The ornamental design for a smartwatch as shown and described.

DESCRIPTION

FIG. 1 is a front, bottom and right side perspective view of a smartwatch showing my new design;

FIG. 2 is a front, bottom and left side perspective view thereof;

FIG. 3 is a rear, top and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings illustrate portions of the smartwatch which form no part of the claimed design.

1 Claim, 9 Drawing Sheets
